ABSTRACT

A new and distinct cultivar of Chrysanthemum plant named Dark Reagan, bearing medium sized pink blooms with a yellow-green center and a performance of 24-28 days.

2 Drawing Sheets**1**

This is a continuation of application Ser. No. 07/780,332 filed Oct. 22, 1991, now abandoned.

The present application is related to the following copending applications and patent:

Application No.	Filing Date	Title
07/780,237	October 22, 1991	Orange Reagan
08/092,941	July 19, 1993	Bronze Reagan
08/101,275	August 2, 1993	Coral Reagan
08/092,942	July 19, 1993	Sulphur Reagan
08/092,943	July 19, 1993	Yellow Reagan
08/088,107	July 8, 1993	White Reagan
08/101,278	August 2, 1993	Salmon Reagan
U.S. Pat. No.	Issue Date	Title
Plant Patent 8,642	March 15, 1994	Reagan

ORIGIN AND HISTORY OF THE NEW PLANT

The new plant of the present invention comprises a new and distinct cultivar of Chrysanthemum plant which is a naturally occurring sport of a Chrysanthemum named Reagan, which in turn is a cross of unknown *Chrysanthemum morifolium* parents. The Chrysanthemum named Reagan is described in U.S. Plant Pat. No. 8,642. The new cultivar was discovered in 1988 as a whole plant mutation in Holland, and has been asexually reproduced by cuttings in greenhouses at Ter Aar, Holland. The new cultivar has been found to retain

25

all of its distinctive characteristics through successive propagations.

SUMMARY OF THE NEW PLANT

5 The present invention is a new and distinct variety of Chrysanthemum of a medium sized bloom and pink color.

BRIEF DESCRIPTION OF THE DRAWINGS

10 The present new and distinct Chrysanthemum cultivar is shown in the accompanying drawings, the color being as nearly true as possible with color photographs of this type.

Sheet 1 shows the full bloom of the new cultivar; Sheet 2, top, shows various stages of bloom of the new cultivar; and

Sheet 2, bottom, shows the foliage and petiole of the new cultivar.

DESCRIPTION OF THE INVENTION

This new variety of Chrysanthemum is of the botanical classification *Chrysanthemum morifolium*, and is named Dark Reagan. When grown in the vicinity of Ter Aar, Holland, it has a response time of approximately 7½ weeks. This new variety produces medium sized pink blooms with a yellow green center having a 4 week performance (i.e., a vase life of 24-28 days). This new variety of Chrysanthemum has been found to retain its distinctive characteristics throughout successive propagations and may be planted under greenhouse

conditions in Holland between weeks fifty and thirty-five (i.e., between December 1 and August 30). Pest resistance, disease resistance and frost tolerance are unknown.

The following is a description of the plant and characteristics (color designations are from R.H.S. Colour Chart) that distinguish it over related known varieties and its antecedents:

Botanical classification: *Chrysanthemum morifolium*.

Bud:

Size.—Medium (cross section ± 1.0 cm, height ± 0.7 cm).

Form.—Round and flat.

Outside color.—Between greyed purple 186 A and 15 B.

Bloom:

Size.—Medium.

Fully expanded.— $6\frac{1}{2}$ –7 cm.

Borne.—Upper portion, single flower per peduncle; 20 Lower portion, plural flowers per peduncle.

Stems.—Strong, thick.

Form.—Single (Daisy).

Performance.—Very good 24–30 days (18°–20° C.).

Color:

Center of flower.—Immature: yellow green 151 C. Mature: yellow green 154 A.

Base of petals.—Red purple 69 B lightly overlaid with red-purple 72 A giving an overall impression of purple 75 A but pinker.

Inside of petals.—Red purple 69 B lightly overlaid with red-purple 72 A giving an overall impression of purple 75 A but pinker.

Reverse of petals.—Red purple 69 C with a light tessellation of red-purple 72 A.

Outer petals.—Red purple 69 B lightly overlaid with red-purple 72 A giving an overall impression of purple 75 A but pinker.

Tonality from a distance.—A pale bronze daisy with a fresh looking center having little or no pollen.

Discoloration.—Some to red purple 69 C.

Pollen.—Yellow-orange 14 A.

Petals:

Texture.—Upperside smooth, underside smooth.

Number.—24–30 (two rows).

Cross-section.—Flat, two keels.

Arrangement.—Imbricated.

Persistence.—Good. Petals keep straight or reflex somewhat at the edge at the end of blooming.

Fragrance.—Typical Chrysanthemum.

Disc diameter.—1.5 cm.

Reproductive organs:

Stamen.—Yellow, thick, 3 mm in length.

Pollen.—Appears at a late stage of blooming, yellow-orange in color.

Styles.—Green, thick. Length.— ± 5 mm.

Stigmas.—Yellow. Width.— ± 1 mm.

Ovaries.—Enclosed in calyx.

Plant:

Form.—Spray mum meant for erect culture. Her- 60 baceous.

Growth.—Strong.

Height.—100–125 cm.

Peduncle.—Near the top ± 14 cm, Near the mid-dle ± 24 cm, Near the bottom ± 28 cm.

Internodes.—3 cm.

Flowering response.— $7\frac{1}{2}$ weeks.

Foliation:

Color.—Upperside green 137 A, Underside 137 C.

Size.—Length ± 12 cm, Width ± 9 cm.

Quantity.—22–28.

Shape.—Lobed, see photograph.

Texture.—Upperside rough, underside smooth slightly hirsute.

Ribs and veins.—Ribs well developed, veins not so developed.

Edge.—Crenated.

Distinguishing characteristics of the Chrysanthemums of the Reagan family are summarized below in Tables IA and IB. Color designations therein are taken from the R.H.S. Colour Chart.
